UNITED STATES PATENT OFFICE.

ELIHU THOMSON, OF NEW BRITAIN, CONNECTICUT, ASSIGNOR TO THE AMERICAN ELECTRIC COMPANY, OF SAME PLACE.

SAFETY SELF-CLOSING SHUNT-SWITCH FOR ELECTRIC-LIGHT CIRCUITS.

SPECIFICATION forming part of Letters Patent No. 275,290, dated April 3, 1883.

Application filed January 22, 1883. (No model.)

To all whom it may concern:

Be it known that I, ELIHU THOMSON, a citizen of the United States, and a resident of New Britain, in the county of Hartford and State of Connecticut, have invented certain new and useful Improvements in Safety Self-Closing Shunt-Switches for Electric Lamps, Motors, &c., of which the following is a specification.

10 My invention relates to electric shunting-switches used in combination with electric lamps, electric motors, or other electric apparatus placed in circuit with a dynamo-machine or other generator or source of electricity, and 15 operated by hand or at will for the purpose of cutting the electric lamp or other apparatus out of circuit.

The object of my invention is to provide a means whereby, in case that portion of the 20 general circuit containing the lamp or other apparatus is interrupted and defective, the shunting-switch will be immediately and automatically reclosed, if under such conditions it be operated to break the shunt and throw 25 the lamp into circuit.

In the practical operation of electric-lighting systems it very often happens that when the shunting-switch of a lamp is opened to throw the lamp into circuit an arc is formed across 30 the switch-contact, owing to an interruption or defect in the lamp-circuit or that portion of the general circuit shunted by the switch. If the switch remain open, the parts will be fused and destroyed and the whole circuit upon 35 which the lamp or lamps are placed will be interrupted.

My invention overcomes this difficulty by providing a means for automatically reclosing the shunt in case the lamp-circuit is interrupted 40 so as to cause an arc to be formed across the switch-contacts, and the switch cannot under such circumstances be turned and the shunt be left open by the attendant or person who attempts to throw the lamp or other apparatus into circuit.

My invention consists in combining with a shunting-switch for an electric lamp or other apparatus suitable mechanism, mechanical or magnetic, which will tend to close the shunt 45 and recomplete the circuit around the lamp or other apparatus, and in controlling the oper-

ation of said restoring device by the agency of the electric current, which flows or is forced into or through the shunt in case an attempt is made to open said shunt while the portion 55 of the general circuit containing the electric lamp or other apparatus is broken or defective.

My invention consists, also, of a special combination in which suitable devices are made to act upon the shunting-switch itself, so as to 60 bring the contacts of said switch itself together in case the current continues to flow in the shunt when the switch is opened, the operation of such device upon the switch being controlled or effected by the agency of the current flowing in the shunt, as will be hereinafter described.

My invention consists, also, of certain specific combinations of devices for carrying out the invention, that will be indicated in the claims. 75

In carrying my invention into practice I propose to depend upon the thermal, the magnetic, or any other effects of the current which may flow into or through the shunt when the switch is turned to break the shunt, and the 75 lamp-circuit or that portion of the general circuit containing the lamp or other apparatus is at the same time broken or defective. I may therefore employ an electro-magnetic coil or helix connected in or to the shunt-circuit; or 80 I may depend upon the thermal effects of the electric current which at the time flows into the shunt. In the latter case I may use an expandible conductor, through which the electric current flows, or I may depend upon the 85 thermal effects of the arc which forms across the shunt-contacts when the shunt is broken, the heat of the arc acting upon a fusible material—such as an alloy—a combustible cord, or upon a thermostatic device consisting of a compound bar or other thermo-mechanical agent. 90

Some of the devices which may be employed for thus utilizing the current flowing in the shunt for effecting or bringing about the closing of the shunt or an automatic restoration 95 of the switch itself to a closed position will be hereinafter described.

The device for acting upon the switch itself or the auxiliary shunt-closer and throwing it to a closed position (the operation of which device is controlled or effected by the agency 100 of the current flowing in the shunt when the

switch is opened) may be either mechanical or magnetic—that is, I may use a spring, weight, or other power, or I may employ magnetic attraction produced preferably by the current itself flowing in the shunt. The latter is the simpler way, as the current flowing in the shunt to control or effect the closing of the switch may then be the agency or power by which the switch is actually thrown.

- 10 In the case of a spring or similar device, suitable detaining mechanism is employed for holding the switch or circuit-closing device open when the conditions are such that the switch may remain open without endangering itself or the continuity of the general circuit, and said detaining mechanism is controlled by the effects (thermal or magnetic) of the electric current flowing in the shunt in such a way that the detaining mechanism shall hold the switch 15 open when no current flows on opening the switch, but shall release or be out of engagement with the switch if under such conditions a current flow.

Some of the various arrangements of the 20 elements employed in carrying out my inventions that may be used are shown in the accompanying drawings, and are illustrated as applied to an electric lamp, although they may be also used with electric motors or other apparatus placed in circuit with a generator or 25 source of electricity so as to be operated thereby.

Figure 1 is a side view of a switch that contains a magnet for automatically throwing the 30 same into closed position. Fig. 2 illustrates a switch containing a spring-actuator and detaining mechanism therefor, controlled by an electro-magnet in the shunt-circuit. Figs. 3 and 4 show the switch of Fig. 2 in the two positions of closed and open. Fig. 5 is a modification in which the thermal effects of the arc formed between the switch-contacts are employed instead of a magnet. Fig. 6 is another modification, in which an expansible conductor 35 is employed in place of the magnet of Fig. 2 and the compound bar of Fig. 5. Fig. 7 shows a modified arrangement of the controlling electro-magnet. Fig. 8 illustrates the manner in which the heating effects of the arc formed at 40 the switch-contacts may cause a release of the circuit-closing device for the shunt by melting a fusible material. Fig. 9 is a modification in which an auxiliary circuit-closing device is used for closing the shunt when the arc forms, 45 instead of the shunting-switch itself, as in Fig. 8. Fig. 10 shows how a combustible or fusible non-conducting film may be used for normally holding the contacts of an auxiliary circuit-closer apart, and may be melted or destroyed when an arc forms between the shunting-switch contacts, so as to allow the shunt to be closed. Fig. 11 shows how a detaining 50 fusible cord is combined with an auxiliary shunt-circuit closer and the shunting-switch.

60 In Fig. 1, A indicates an electric lamp or equivalent apparatus in the general circuit 9 of a generator or source of electricity, while L

indicates the lever of the shunting-switch, which is of any desirable shape or form, is operated by a button or knob, 12, and is connected to the general circuit 9 9, so that when it closes circuit at S B in the usual way it will cut the lamp out of circuit by completing a shunt or short circuit around it. M indicates an electro-magnet which is in the shunt or short circuit, one end of its coil being connected to the pivot of the switch-lever L, while the other end is connected directly to the general circuit, as indicated. The electro-magnet M is mounted on the switch-lever L, while its armature M² is fixed in any suitable manner, and acts to draw the electro-magnet and switch-lever toward the contact B whenever current flows through the coils of M. Suitable stops limit the movement of the switch-lever. When the shunting-switch is opened, if no adequate passage exist for the current at A, the current, passing or arcing over the switch-contacts at B S and circulating through the coils M, will draw the switch-lever over and restore the contact 90 at B S the moment the hand of the person operating it is withdrawn. The continuity of the general circuit will thus be automatically preserved and the destruction of the switch prevented. The device is especially valuable when the switch-contacts are out of sight, so that an arc, if formed, cannot be seen, so as to give warning of the defective circuit in A, or when the apparatus is in the hands of ignorant persons.

In Fig. 2 a spring, Z, is used for drawing the lever L over to close the shunt, in place of the armature M². The electro-magnet M acts to hold a detaining device for the lever out of engagement therewith when current flows through the coils of the electro-magnet. N is the armature-lever of the electro-magnet M, which lever carries or controls a catch, C, that tends to engage with a notch or shoulder at C² on the switch-lever L when the armature-lever N is retracted, and when so engaged detains the lever L in the position shown in Fig. 4 and prevents the spring Z from drawing the lever over so as to close the shunt-circuit at B S. A depending chain or cord, C¹, may be provided for the purpose of disengaging the catch when it is desired to shunt the lamp. When the lamp is shunted the parts are in the position shown in Fig. 3 and the switch is held over by spring Z. When the lever is turned to start the lamp and current still flows across the switch-surface B S and through coils M, owing to an inadequate path in A, the spring Z will act to restore the switch immediately when the hand is removed, because the electro-magnet M will hold the detaining devices out of engagement. If, however, the circuit through A is complete, the current will cease to flow through the shunt the moment that B and S are separated, so that the catch C will engage with C² and hold the lever L back until the armature-lever is drawn down by hand or other means independent of the electro-magnet M.

In Fig. 5 a compound bar of dissimilar metals—such as is used for thermostats, thermometers, and other thermo-mechanical devices—takes the place of the electro-magnet M, and is arranged in suitable proximity to the shunting-switch contacts B S, so as to become heated by any arc that may form between said contacts. B² indicates the compound bar, which is fixed at one end by any suitable means, and at its free end is connected by a link, l, with a lever carrying the catch C. The parts are so set and arranged that the elasticity of the bar B² when not heated tends to draw up the catch C and thus detain the lever L when the latter breaks the shunt without forming the arc. If, however, through the breaking of the circuit in A, an arc form at B S, the bar is heated and lowers the catch C, so as to carry it away from a point where it will engage the lever L, thus allowing the spring, when the hand is removed, to immediately restore the lever to the position in which it will close the shunt.

In Fig. 6 an expansible conducting-wire, D², in the shunt-circuit serves to control the detaining device and the switch. When the current flows through the shunt the wire D² is lengthened and the catch C is lowered away from its engaging position. If, however, the shunt is broken at B S, when the lever L is turned the wire shortens and draws up the catch, so that it will engage with and hold the lever back when the hand is removed. A spring, D³, gives the requisite elasticity to the support for C, so that it can be disengaged by pulling on the chain or cord C⁴.

In Fig. 7 the electro-magnet M is not in the direct shunt-circuit with the switch-contacts proper; but an accessory plate, S², is provided, near which the upper end of L moves. The electro-magnet M is placed in a circuit, 15, from 9 to S². When the switch-contact S is opened with an arc the arc is transferred to the nearer plate, S², thus putting the electro-magnet M into circuit, so that it will attract the armature N and reclose the switch. This arrangement of the plates S², S, and L might be used with the other mechanical or electrical devices herein described.

In Fig. 8 the thermal effects of any arc forming between the shunting-switch contacts are utilized for releasing a shunt-circuit closer. The switch-plate L is made in two parts, hinged together at B⁴, and the hinge is soldered with some readily-fusible material or alloy. The joint or hinge B⁴ is sufficiently near the points B S to be heated quickly by any arc that may form. So long as the soldered or cemented joint at B⁴ remains intact the switch may be operated in the ordinary way, and will retain the position shown in full lines when thrown to such position by hand or otherwise. If, however, in opening the switch an arc forms at S, the heat softens or melts the solder or cement at B⁴, and the spring Z is then free to act so as to close the contact at B S.

In Fig. 9 the fusible material which controls

the action of the device which serves to close the shunt, if a current continues to flow in it after the switch is turned, is applied in a little different way. In this case, as in Figs. 10 and 11, an auxiliary shunt-circuit closer is employed; but the principle of operation is the same as when the shunting-switch proper is controlled. W indicates a strained elastic wire, mounted on lever L and in electric connection therewith. A pin or stud, b, of some readily-fusible material, holds the spring in the position shown by the full line. This pin is fused whenever an arc is formed between the switch-surfaces S B, thus releasing the wire or spring W, which by its own elasticity is brought into contact with B, or a stud, D, thereon, thus closing the shunt.

In Fig. 10 a conducting-plate, H², is attached to contact B, as shown, and carries a sheet or film of an insulating combustible or fusible material, F—such as paper or wax—which serves to normally keep a spring, G, out of electrical connection with the plate. Spring G is connected, as shown, so that when it makes contact with H² the lamp or other device at A is shunted. If an arc form between L and B, the sheet of paper or other material is carbonized, softened, or melted, so that the spring G can penetrate to the plate H², and thus close and preserve the shunt, and also prevent destruction of the contacts S, L, and B by the arc.

In Fig. 11 a string or wire, K, of fusible or combustible material, is employed as the means for controlling the operation of the device, which closes the shunt when the opening of the switch does not produce a break of the shunt-circuit. G is the spring circuit-closer, 105 which is held out of contact with stop H² by the fusible connection K, but which is so connected, as shown, as to close a shunt when it comes into contact with H². The cord or wire K is arranged in suitable proximity to the switch contacts S B, so that if an arc form on opening the switch, the cord or wire will be burned or fused, and will thus allow the circuit-closer to act and close the shunt-circuit.

Many other devices for carrying out my invention will readily suggest themselves to those skilled in the art, and I do not therefore limit myself to any special forms of circuit-closers or of electrical, thermal, or other devices that may be arranged to be affected by the current circulating in the shunt when the shunting-switch is opened, and to control or cause the operation of the shunting switch proper or of an auxiliary shunting-switch.

I make no specific claim herein to the specific combinations of devices in which the thermal effects of the current circulating in the shunt after the shunting-switch is opened are utilized for controlling or causing the operation of the shunting or auxiliary switch, so as to cause an immediate reclosing of the shunt, as this forms the subject of another of my applications for patent.

What I claim as my invention is—

1. The combination, with an electric lamp or other apparatus, as described, in circuit with a generator or source of electricity, of a shunting-switch, circuit-closing devices for closing the shunt, actuated or controlled by the effects of the electric current which may flow in the shunt after the opening of the shunting-switch, substantially as and for the purpose described. 50
- 15 2. The combination, with an electric lamp or other apparatus, as described, of a shunting-switch, devices for closing said shunt, and means for actuating or allowing the operation of said devices so as to complete a shunt-circuit upon the passage of a current across the contacts of the shunting-switch on opening the same. 55
- 20 3. The combination, with an electric lamp or other apparatus, as described, of a shunting-switch, devices for automatically bringing the contacts of said switch together in case the current continues to flow in the shunt after the switch is opened, the operation of such devices upon the switch being controlled or effected by the agency of the current flowing, substantially as and for the purpose described. 60
- 25 4. The combination, with an electric lamp or other apparatus, as described, of a shunting-switch, devices for restoring said switch to a closed position when it is opened, and means for bringing said devices into operation to close said switch upon the passage of a current across the switch-contacts at the time of opening the switch. 65
- 30 5. The combination, with an electric lamp or other electric apparatus, as described, of a shunting-switch, means for restoring said switch to a shunting position, and a helix in or connected to the shunt-circuit, so as to be energized when a current passes through said shunt, and controlling the operation of the restoring mechanism, so as to prevent said switch from remaining in opened position while current is forced across the contacts by reason of the rupture or imperfection of that portion of the general circuit containing the lamp. 70
- 35 6. The combination, with an electric lamp or other electric apparatus, of a shunt-switch, a device, magnetic or mechanical, for closing 75
- 40 said switch automatically, and an electric coil in the shunt-circuit controlling the action of the closing device and causing or allowing the operation of said device to immediately reclose the switch whenever on opening the same the main or principal circuit is interrupted or defective, so as to cause a current to pass the switch-contacts as they are separated. 80
- 45 7. The combination, with an electric lamp or other apparatus, as described, of a shunting-switch, a spring or equivalent motor tending to close the switch, a detaining device for holding the said switch open, and means for controlling the action of said detaining device in the manner described, so as to release the switch whenever a current flows across the switch-contacts on opening the switch. 85
- 50 8. The combination, with an electric lamp or other apparatus in circuit with a suitable source of electricity, of a shunting-switch, a spring or equivalent device tending to close the switch, a catch for engaging with the switch and holding it open when said switch is thrown back to break the shunt, and suitable means, as described, for holding the catch away from the point where it will engage with the switch, energized or rendered operative for the purpose by the current which flows through the shunt across the switch-contacts when the switch is turned to break the shunt. 90
- 55 9. The combination, with an electric lamp or other device in circuit with a suitable source of electricity, of a shunting-switch for said device, a spring or its equivalent tending to close the switch, a catch for engaging with the switch when it is thrown to break the shunt, and an electro-magnet connected to the shunt-circuit, so as to be energized when a current passes the separated contacts of the switch, and when so energized holding the catch away from its engaging position. 95

Signed at New Britain, in the county of Hartford and State of Connecticut, this 17th day of January, A. D. 1883.
